UNITED STATES PATENT OFFICE.

LEGER J. CASTONGUAY, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

INCANDESCENT-LAMP SOCKET.

1,046,968.

Specification of Letters Patent.

Patented Dec. 10, 1912.

Application filed January 21, 1910, Serial No. 539,225. Renewed September 15, 1910. Serial No. 582,321.

To all whom it may concern:

Be it known that I, LEGER J. CASTONGUAY, a citizen of the United States of America, residing in the city of Bridgeport, 5 in the county of Fairfield, and in the State of Connecticut, have invented certain new and useful Improvements in Incandescent-Lamp Sockets, of which the following is a specification.

10 The main object of my invention is to so construct an incandescent lamp key socket as to lessen the cost of manufacture, simplify the construction and increase its durability. This object I attain by the construction which I will now describe.

In the accompanying drawings Figure 1 is a vertical section of a key socket embodying my invention of the type in which the insulating body is made in two pieces, the 20 lined inclosing shell and cap being omitted for the sake of simplicity; Fig. 2 is a similar view showing the key turned to the "off" position; Fig. 3 is an inner face view of the upper insulating block detached; Fig. 4 is 25 an inner face view of the lower insulating block with the switch key removed; Fig. 5 is a sectional view of a socket of the single insulating block type, embodying my invention; Fig. 6 is an inner face view of the 30 single block with the screw shell, center terminal and key removed.

Referring to Figs. 1 to 4, the lower insulating block A may carry any suitable form of lamp-receiving terminals, such as the 35 ordinary screw shell S and central spring contact C. The inner face of the lower block has a suitable recess or chamber a to receive a contact plate D, shown in this case as in electrical connection with the lamp terminal contact C through a central screw 10. The key spindle E which carries 40 at its outer end the oblong switch block F with the usual lost motion or play, is not mounted, as is the more common plan, in a metallic frame, but finds a bearing in a 45 washer e¹, preferably of insulating material set in semi-circular recesses b, (Figs. 3 and 4), in the adjacent faces of the lower block A and upper block B. For the rest the spindle is guided with a certain amount of 50 freedom in transverse grooves b¹, b², (Figs. 3 and 4), in the adjacent faces of the two blocks. The inner face of the upper block B is provided with a recess g over the switch

block F and this recess may be of the curved 55 form best illustrated in Fig. 3, to receive the spring contact G, which is held in place by having its outer end 11 clamped between the upper end of the bracket 12 and the porcelain of the upper block. The two 60 brackets 12 and 13 are adapted to receive binding screws 14 and 15, (Fig. 4), for the terminal wires and such brackets may be of the construction employed in the well-known 65 Perkins socket of the Perkins Patent 626,927, to also unite the blocks together mechanically. The bracket 13 will be in electrical connection with the lamp-receiving screw shell S, while the bracket 12 will be in electrical connection with the central contact of 70 the lamp socket through the spring contact G, switch block F, contact D, and screw 10, when the switch block is turned to the position illustrated in Fig. 1. In connection with the switch key I provide a spiral 75 spring P held in a recess in the inner face of the upper block B and adapted to bear at its lower end upon the switch spindle directly or indirectly. When the switch key is turned from the position shown in Fig. 1 80 to that shown in Fig. 2 the circuit will be broken by the oblong block F leaving the spring contact G, being pressed away therefrom and against the contact plate D by the spring P.

It will be seen from the above described 85 construction that the metallic frame employed in the majority of sockets for the key spindle is dispensed with, and the manufacture correspondingly simplified and made 90 more economical.

The spring P does only mechanical work 95 in the switch mechanism, and forms no part of the electric circuit, and being a spiral spring it is more durable and efficient and smoother in its action than the spring contact plates which are usually employed for the double purpose of mechanically actuating the switch block to get a quick break and for conducting current.

100 Although I prefer to embody my invention in a socket of the Perkins two-block type, it will be understood that it may be embodied in other constructions of socket, and in Figs. 5 and 6 I have illustrated its 105 application to a single block type of socket. In this construction the switch block F¹ on the outer end of the key spindle E¹ makes

electrical connection in the position shown in Fig. 5 between the lamp-receiving shell S¹ and the spring contact G¹ set into a right-
angular recess g¹ formed in the inner face
5 of the block B¹. This contact plate G¹ is
in electrical connection with a binding post
16; the other binding post will be in direct
electrical connection or formed in one with
the central lamp contact C¹, Fig. 5. The key
10 spindle E¹ finds a bearing in a washer e¹
set in a recess in the inner face of the block
B¹. A tongue 17, formed in one with the
screw shell S¹, or fixed thereto, may sup-
port the spindle E¹. A spring P¹, which
15 bears at its upper end against a disk p of
insulating material set into a recess in the
inner face of the block B¹, bears at its lower
end against the key spindle E¹ in such a way
that when the key is turned to carry the
20 block F¹ from the vertical position shown
in Fig. 5 the spring will cause the block to
lie horizontally against the flange of the
screw shell S¹ and out of contact with the
plate G¹ substantially in the manner indi-
25 cated in Fig. 2 with reference to the con-
struction previously described.

I claim as my invention—

1. A key socket having a key spindle with
a contact block, an insulating body recessed
30 to receive and guide the key spindle, with
contacts, between which the switch block

makes electrical connection, and a spiral
spring to act on the spindle to press the
block away from one of the contacts when
the key is turned to break the circuit. 35

2. A key socket having a spindle and
switch block, an insulating body recessed to
receive and guide the key spindle, contacts
between which the switch block makes
40 electrical connection, one of said contacts
being a spring contact, and a spiral spring
to act upon the key spindle to press the
switch block away from the spring contact
when the key is turned to break the circuit. 45

3. A key socket, having a key spindle and
switch block and a bearing washer for the
key spindle, an insulating body recessed to
receive and hold the said washer and re-
cessed to receive and guide the spindle, contacts
50 between which the switch block makes
electrical connection and a spiral spring to
act upon the key spindle to press the block
away from one of the contacts when the key
is turned to break the circuit. 50

In testimony whereof I have signed my
name to this specification, in the presence
of two subscribing witnesses. 55

LEGER J. CASTONGUAY.
